UNITED STATES PATENT OFFICE.

WILLIAM H. SOMMER, OF PEORIA, ILLINOIS, ASSIGNOR, BY MESNE ASSIGNMENTS, TO THE UNION TRUST COMPANY, OF CLEVELAND, OHIO, A CORPORATION OF OHIO, AND JOHN A. CHAPMAN, OF CHICAGO, ILLINOIS, TRUSTEES.

OPEN-HEARTH FURNACE

1,407,004.

Specification of Letters Patent. Patented Feb. 21, 1922.

Application filed March 5, 1919. Serial No. 280,788.

To all whom it may concern:

Be it known that I, WILLIAM H. SOMMER, a citizen of the United States, residing at Peoria, in the county of Peoria and State 5 of Illinois, have invented new and useful Improvements in Open-Hearth Furnaces, of which the following is a specification.

This invention has reference to open-hearth furnaces, and it relates particularly 10 to a protecting wall for the back wall of the furnace. Said protecting wall comprising a fixed part which is coincident with the "buck-stays", and a movable part situated between each set of "buck-stays."

15 It is common knowledge, in open-hearth practice, that it is necessary to replace back-walls because of deterioration, and at times, on account of the back-wall falling in. If a back-wall gives way during a heat, the heat 20 will "freeze", entailing considerable loss, and therefore, it is the practice that if the operator sees that the back-wall will give before a heat can be consummated, he will 25 shut the furnace down until a new back-wall is built.

My invention is intended, first, to protect 30 that portion of the back-wall coincident with each set of "buck-stays", by a wall built up in front of each set of "buck-stays" and being 35 bound thereto; and second, to protect that portion of the furnace, coincident with the back-wall between each set of buck-stays, by a movable shield or wall which is used to cover the deteriorated, or fallen wall. Said 40 movable shield or wall serves also, to protect the working men during the rebuilding of the wall, in case it is desirable to reconstruct the back-wall, between the sets of "buck-stays" during a heat.

45 That the invention may be more fully understood reference is had to the accompanying drawings, in which:—

Figure 1 is a rear elevation of a part of an open-hearth furnace, with my invention 45 applied thereto;

Figure 2 is a cross-section through a furnace, showing my invention applied to the rear wall;

Figure 3 is a detail cross-section, in plan 50 showing the wall construction coincident with a set of buck-stays, and part of two movable wall sections, one on either side of the set of buck-stays;

Figure 4 is a detail, in elevation, as the

same would appear on the line 4—4 Figure 55 3 looking in the direction of the arrows;

Figure 5 is a detail cross-section, in elevation, as the same would appear on the line 5—5 Figure 4;

Figure 6 is an elevation of one of the 60 movable shields or walls, part of the refractory facing broken away, and

Figure 7 is a cross-section, as the same would appear on the line 7—7 Figure 6.

Like characters denote corresponding 65 parts throughout the figures.

In the drawings, 1 designates an open-hearth furnace of well known construction having the back-wall 2. This back-wall is faced by a series of sets of "buck-stays". 70 Each set of stays comprise, preferably, three stays; the middle one being an I beam 3 and the others channel beams 4. The channels of these beams face each other, and the channels of the I beam. The upper ends of the 75 stays 3 and 4 are connected to longitudinally arranged channel-beams 5.

Before, or at the time of building the back-wall 2 of the furnace a wall 6 is built up in front of each set of "buck-stays" 3, 4, 80 and the back-wall 2 is off-set therearound, as at 7, see Figure 3, so that the face of the back-wall 2 is in the same vertical plane with the front face of the stays 3, 4, except where the same is offset as at 7. The wall 6 is 85 made, preferably, of refractory brick, the same as the back-wall 2, and between each layer of brick in the wall 6 are laid the binding plates 8, of a suitable material, each of which have parts 9 complementary to the 90 channels in the stays 3 and 4 and extending therebetween, see Figure 3. The front and sides of the wall 6 is preferably faced with a facing 10 made of asbestos or other heat insulating material to prevent fusing of the 95 walls 2 and 6, as will be understood.

It is obvious, that when the back-wall 2 which is coincident with the wall 6 becomes deteriorated, or falls, that the wall 6 serves as the back-wall to protect the heat, and may 100 be used in lieu of the wall 2, until it is desirable or convenient to rebuild or replace the same. The wall 6 will out last the wall 2 and need not, therefore, be replaced as often.

105 The movable shield or wall is designated 11, and its detailed construction is best seen in Figures 6 and 7. I prefer to construct

the shield with top and bottom and end flanges 12, 13 and 14, 14, the last named being connected by the longitudinally arranged spaced ribs 15 united with the rear 5 wall of said shield by the webs 16, and the rear wall is preferably provided with the plurality of openings 17 as a ventilating means to cool the wall 18 of refractory material filling the pockets of the shield, formed 10 by the ribs 15, webs 16 and rear wall of said shield. To the upper flange 12 are secured the eye-rings 19 to which are connected sections 20 of a chain 21 which rides over a pulley-wheel 22 and to the end of the chain 15 21 is secured a counter-balancing weight 22' to hold the shield in its different positions.

The shields 11 are independent of each other and may be lowered into position to protect a deteriorated portion of the back-wall 2, or 20 to take the place of fallen part of said wall 2 to protect a heat, or a brick mason when repairing the wall 2.

What I claim is:—

1. In combination with an open hearth 25 furnace having spaced sets of "buck-stays", walls interlocked with said sets of "buck-stays", and shields movably supported between said sets of "buck-stays".

2. In combination with an open hearth 30 furnace having spaced sets of "buck-stays", walls of refractory material interlocked with said sets of "buck-stays", shields movably supported between said sets of "buck-stays", and a wall of refractory material inter- 35 locked in each of said shields and forming a facing therefor.

3. In an open hearth furnace, in combination, a back-wall of the furnace formed with vertically arranged spaced recesses, a group 40 of "buck-stays" coincident with each recess, and a wall built up in front of each group of "buck-stays" and disposed in said recesses.

4. In an open hearth furnace, in combination 45 a back-wall of the furnace formed with vertically arranged spaced recesses, a group of "buck-stays" coincident with each recess, a wall built up in front of each group of "buck-stays" and disposed in said recesses, and a facing for each of said last mentioned walls of heat insulating material.

5. In an open hearth, in combination, a back-wall of the furnace formed with vertically arranged spaced recesses, a group 55 of "buck-stays" coincident with each recess, a wall built up in front of each group of "buck-stays" and disposed in said recesses, and a shield movably supported between each group of "buck-stays."

6. In an open hearth furnace, in combination, a back-wall of the furnace formed with vertically arranged spaced recesses, a group 60 of "buck-stays" coincident with each recess, a wall of refractory material built up in front of each group of "buck-stays"

and disposed in said recesses, and a shield movably supported between each group of "buck-stays", each shield having a facing of refractory material.

7. In combination with the "buck-stays" 70 of an open hearth furnace, a wall forming a facing for said "buck-stays" between said "buck-stays" and the furnace wall, and means for binding said facing wall to said "buck-stays".

8. In combination with the "buck-stays" 75 of an open hearth furnace, a wall of refractory material forming a facing for said "buck-stays" between said "buck-stays" and the furnace wall, and means for binding 80 said facing wall to said "buck-stays".

9. In combination with the "buck-stays" 85 of an open hearth furnace, a wall of refractory material forming a facing for said "buck-stays", a heat insulating material covering the exposed surfaces of said wall, and means for binding said wall to said "buck-stays".

10. In combination with an open hearth 90 furnace, a group of "buck-stays" having matching channels, a wall comprising layers of refractory brick, and plates between each layer of brick, each plate having a part complementary to the channels of said "buck-stays" and forming a binder for said wall. 95

11. A shield for the purposes specified, said shield having pockets formed by spaced flanges each having a locking element, and a facing for said shield made of refractory material and interlocked with said 100 flanges and their locking elements and covering the latter.

12. In combination with an open hearth furnace having spaced sets of "buck-stays", walls forming a facing coincident with each 105 set of "buck-stays", a shield movably supported between each set of "buck-stays", and counterbalancing means for each shield.

13. In combination with an open hearth 110 furnace having spaced sets of "buck-stays", a wall section coincident with each set of "buck-stays" and independent from the furnace wall, and means for interlocking said wall sections with their respective set of "buck-stays".

14. In combination with an open hearth furnace having spaced sets of "buck-stays", a wall section coincident with each set of "buck-stays" disposed between the "buck- 120 stays" and furnace wall and independent from the latter.

15. In combination with an open hearth furnace having spaced sets of "buck-stays", a wall section coincident with each set of "buck-stays" disposed between the "buck- 125 stays" and furnace wall and independent from the latter, and a facing for said wall sections to prevent fusing of said wall sections with the furnace wall.

WILLIAM H. SOMMER.
